United States Patent

Des. 238,877

Patented Feb. 17, 1976

238,877

ALCOHOL BURNER AND CAP THEREFOR

Robert Maddestra, Canton, and David E. Munn, Framingham, Mass., assignors to Damon Corporation, Needham Heights, Mass.

Filed Aug. 14, 1974, Ser. No. 497,197

Term of patent 14 years

Int. Cl. D7—02; D23—03
U.S. Cl. D23—72

FIG. 1.

FIG. 2.

FIG. 3.

FIG. 4.

FIG. 5.

FIG. 1 is a perspective view of an alcohol burner and cap therefor showing the new design with the cap removed for ease of illustration;

FIG. 2 is a front elevation view thereof with the cap removed for convenience of illustration;

FIG. 3 is a bottom plan view thereof;

FIG. 4 is a side elevational view thereof, again with the cap removed for ease of illustration; and

FIG. 5 is a perspective view thereof with the cap in place.

We claim:

The ornamental design for an alcohol burner and cap therefor, as shown.
